HENRY H. HAMILTON, OF COLUMBUS, OHIO.

METHOD AND APPARATUS FOR FEEDING COAL.

Continuation of application Serial No. 611,598, filed January 9, 1923. This application filed June 16, 1923. Serial No. 645,743.

My invention relates to a method and apparatus for feeding coal, and has to do particularly with the provision of a novel method and apparatus for elevating and projecting coal into a fire box and automatically distributing such coal to various desired points over the furnace grate.

In the feeding of coal to locomotive fire boxes by means of automatic stoker mechanism, it has been customary to convey the coal to a certain point adjacent the fire box and then to elevate the coal up to a point from where it may be conveniently projected or fed into the furnace. This projection or feeding of the coal has hitherto been accomplished by means of steam jets, compressed air, mechanically operated arms, et cetera. Furthermore, this coal has been projected towards the rear of the furnace or grate structure in substantially one path, thus leaving the part of the grate structure adjacent the fire doors or the front of the fire box practically free from coal. These structures for conveying and feeding the coal are not only expensive and complicated but the coal is not distributed to the most efficient points over the grate area after it is once projected into the furnace.

I have met and solved the problem of feeding and distributing the coal in a different way. Instead of conveying the coal to a point adjacent the fire box and then elevating the coal to another point, I have discovered that this coal can be simultaneously elevated and projected into the furnace with one continuous motion. Therefore, I have devised an apparatus for feeding coal which preferably takes the form of a cylindrical casing structure provided with revolving paddles of novel arrangement and design. The inlet and outlet of this hopper structure are so designed that momentum is imparted to the coal without any crushing thereof and this imparted momentum is utilized to project the coal directly into the fire box.

My device is further provided, preferably just inside the fire box wall, with means for deflecting and distributing the projected coal to different desired points over the grate surface. This deflecting means is such that the fine coal will be initially separated from the coarser coal and will be distributed across the front of the furnace while the lumps of coal will be preferably intermittently deflected and distributed to various points from

the extreme front of the furnace to the extreme rear thereof.

This application is a continuation of application Serial No. 611,598, filed January 9, 1923.

The device which I preferably utilize in my novel method of feeding and distributing coal is shown in the accompanying drawings wherein similar characters of reference designate corresponding parts, and wherein:

Figure 1 is a side elevation, partly diagrammatic and sectional, of my novel coal feeding and distributing device, showing the preferred manner of connecting this device to the locomotive.

Figure 2 is a plan view, partly cut away and partly in section, substantially on line 2-2 of Figure 1, showing the method of feeding coal to two separate units for the subsequent elevation and projection of such coal into the fire box.

Figure 3 is an enlarged diagrammatic and fragmentary rear elevation of the mechanism for controlling the operation of the deflecting means, showing the manner of adjusting such deflecting means to vary both the path and the stroke thereof.

Figure 4 is a fragmentary plan view of the structure shown in Figure 3, showing the manner of positioning the coal deflector over the coal inlet and also showing the manner of admitting a fluid to such deflector structure to both cool said structure and separate the fine coal as it is projected into the furnace.

In the drawings, and referring particularly to Figures 1 and 2, my coal feeding apparatus is shown as comprising preferably cylindrical casings which may be designated 1 and 2. These casings are preferably arranged adjacent the opposite sides of the locomotive fire box 3 and are preferably provided with a single shaft 4 which shaft is preferably located just below the firing floor of the locomotive cab.

Designed to be carried by the shaft 4 and to be rotated within the casing structures 1 and 2 are a series of paddles 5 and 6 respectively carried by hubs 7 and 8. Coal is conveyed to these casings 1 and 2 by means of a suitable spiral conveyor 9. The conduit for this spiral conveyor 9 and the coal conveyed thereby are preferably divided into conduits 10 and 11, which conduits enter their respective casings 1 and 2 and as shown in Figure

2, I prefer to locate the outlet of these conveyor conduits downward and to one side of the axis 4.

The paddles 5 and 6 may be rotated by any suitable motive power applied to the shaft 4 and as indicated by Figure 1 these paddles are revolved in a clockwise direction. The outer ends of the paddles 5 and 6 are preferably enlarged so that the edges of each paddle are substantially flush with the side walls of the respective casings 1 and 2. The base of each paddle may be cut away as at 12 so that that narrow part of each paddle which will pass by the outlet of the conveyor conduit 10 or 11 will always be a substantial distance away from the outlet. Thus, it will be obvious that any coal discharged from the conduits 10 and 11 into the casings 1 and 2 will tend to drop down towards the bottom 20 of the casing and between the outer broad edges of the paddles 5 and 6 as they pass by the outlets of such conduits, as is best illustrated in Figure 1.

The casings 1 and 2 are preferably mounted upon a base structure 13 in such a manner that they will extend longitudinally in the general direction of the locomotive and also so that the conveyor 9 will be located below the floor of the locomotive cab. Connected 30 to each of the casings 1 and 2 as at 14, I have provided an upwardly and forwardly extending conduit 15 for conveying the coal forward into the fire box as it is elevated and thrown from each successive blade 5 and 6. Each 35 conduit 15 merges with the periphery of the casings 1 and 2 so as to continue the gradual curve of such casings until the conduits enter the fire box. This gradual curve of the conduit is so formed that the coal will be projected directly into the fire box with a momentum which will be determined by the R. P. M. of the paddle blades, the radius and the size of the lumps of coal.

Positioned inside of the front wall 3 of the fire box and designed to be suspended in front of the outlets of the conduits 15, I have provided deflecting elements 16 and 17. These deflecting elements 16 and 17 are carried by hollow lever arms 18 and 19 which also comprise right-angled hollow extensions 20 pivotally carried by suitable bearings 21 mounted on the front wall of the locomotive fire box 3. The outer end of this hollow projection 20 is connected with a suitable non-rotary or flexible ball joint 22 which in turn is connected with a suitable pipe and valve structure 23 for the variable admission of steam or water in any desired form. Keyed to the outer end of the projection 20, at a point between the fire box wall 3 and the joint 22, is an arm 24. This arm 24 is adjustably connected by means of holes 25 to a vertically positioned link 26. This link 26 is pivotally connected to a lever 27 which in turn is oscillated about 60 a fulcrum 28 by means of a vertically recip-

rocable rod 29, which is so reciprocated by means of an eccentric structure 30 connected to a suitable driven shaft 31. It will thus be obvious that when the rod 29 is vertically reciprocated the link structure 24, 26 and 27 will be effective to simultaneously oscillate the deflector 16 vertically up and down in front of the conduit 15. The fulcrum 28 is adjustable by means of a suitable screw structure 32 and lock nuts 33 whereby it will be possible to change the path of the deflector 16 by merely adjusting the screw element 32 or it will be possible to change the length of said path by adjusting the upper end of the link 26 in one of the various holes 25.

The deflector elements 16 and 17 are preferably made of material of high heat resisting qualities and are also preferably hollow. As best shown in Figure 1 the deflector elements 85 preferably extend vertically downward for a portion of their length and are then inclined at an angle for the remainder of their length.

As best shown in Figures 3 and 4, at the top of the deflector elements 16 and 17 and positioned along the side adjacent the conduits 15, I have provided a series of outlet orifices 34 which are so positioned that any steam or water passing through the hollow supporting arms 18 and 19 will be projected downwardly in the form of small streams preferably at right angles to the path of the coal being projected into the furnace. The deflector elements 16 and 17 may also be formed to present convex or angular surfaces to the oncoming fuel to insure proper distribution laterally with reference to the general direction of projection of the coal. It will be understood that the structure for operating and controlling the movement of the deflector 17 is symmetrical in form and arrangement to the 100 structure as above described and as shown in Figure 3.

In operation, the coal is conveyed to the casings 1 and 2 by means of the spiral conveyor 9, it being understood that this spiral conveyor may be operated in the usual way and at any desired speed to furnish the conduits 10 and 11 with the casings 1 and 2 with the required amount and kind of coal desired. As the coal is discharged from the conduits 10 and 11 the lumps and particles of coal are dropped downwardly towards the bottom of the casing and between the revolving blades 5 and 6. A definite amount of coal will thus be fed into the casings and be caught between two of the blades 5 or 6 so that when these blades are revolved this definite amount of coal will be carried round towards the top of the casing by means of the broad outer edges of these blades. The paddle structures 115 or blades 5 and 6 may be rotated at any desired speed so that the coal carried by each blade will be projected forward through the conduit 15 and directly into the fire box 3 as the blade passes the point 14, where a definite 120

velocity is imparted to the particles of coal in accordance with the velocity of the blades, the radius and the tangential action produced as the coal leaves the blades. The continued 5 revolution of each of the paddle structures will thus cause a practically continuous stream or body of coal to be elevated and directly projected into the furnace. In order 10 to properly distribute the coal as it is projected into the furnace I have provided vertically reciprocable elements 16 and 17. As power is applied to the shaft 31, the rod 29 and the connected link structure will be effective to oscillate the hollow lever arms 18 and 19 about 15 the axes formed by the bearing structures 21. This raising and lowering of the deflector elements 16 and 17 in front of the conduits 15 is so timed in relation to the revolution of the paddle structures that the projected coal will 20 be intermittently deflected from its general path. In normal position the bottom of the deflector 16 is adjacent to the top of the conduit structure 15 so that before the deflector element is lowered the main body of the coal 25 will be preferably projected to the rear of the grate surface. As the deflector 16 is lowered the particles of coal will be gradually deflected and distributed towards the front of the furnace until the deflector has been lowered 30 to its approximate lower position when the greater part of the coal will be deflected and distributed to the immediate front of the grate surface. The fluid, preferably steam, passing through the hollow supporting arms 35 18 and 19 will issue from the plurality of small orifices 34 in the form of small jets. These jets of fluid will pass downwardly at right angles through the path of the projected coal at all times so that the finer particles 40 of coal will be separated and distributed over the grate surface at the front of such grate, regardless of the position of the deflector element 16. Thus this fluid not only tends to 45 relatively cool the deflector elements and their supporting arms 18 and 19, to protect them from the resulting heat in the fire box, but also to separate substantially all of the finer particles of coal and keep them from passing up through the smoke stack by virtue of the 50 strong draft which is always present in locomotive furnace structures.

It will be understood that the hopper or casing structures may be of any desired form and of any desired number whereby the coal 55 may be introduced into the fire box at any number of desired points. Also the paddle blades 5 and 6 may be of any desired structure whereby they will be able to impart momentum to the coal preferably without crushing 60 such particles during their operation of elevating and projecting such coal.

It will also be understood that the deflector elements 16 and 17 may be of any desired shape and size, as it will be obvious that a 65 different size or shape of deflector would be

preferred in deflecting coal of different sizes and also when deflecting and distributing coal to various sizes of furnaces and grate structures. It will further be understood that the deflector elements 16 and 17 may be independently operated instead of being connected to the same lever arm 26 as is shown in Figure 3.

It will be seen that I have provided a novel and decidedly simple stoker for feeding and distributing coal which is effective to automatically and continuously elevate, project and distribute the coal with one continuous motion. It will be further noted that I have provided a feeding structure which not only elevates the coal and utilizes this elevating action to impart momentum to the coal but also that the coal is projected directly into the fire box with substantially no loss of such imparted momentum. It will further be obvious that I have provided a method and means wherein this directly projected coal may be automatically distributed to all points of the furnace structure while at the same time separating and distributing the finer particles of 70 coal from the main distributed mass of coal. It will also be obvious that by providing means for varying the path, or the length of the path, of the deflector, or a combination of both, I have provided a structure that may be adjusted to take care of any variations in the size of the furnace, the length of the grate surface, the velocity or kind of fuel fed or projected and the point at which said fuel is 75 projected into the fire box.

Having thus described my invention, what I claim is:

1. The method of feeding coal which consists in elevating and projecting the coal into the furnace with one continuous motion, separating the fine coal from the coarse coal and delivering the coarse coal to predetermined areas of the furnace.

2. The method of feeding coal which consists in elevating and projecting coal into the furnace with one continuous motion, separating the fine coal from the coarse, and simultaneously deflecting such coarse projected coal.

3. The method of feeding coal which consists in elevating and projecting the coal into the furnace with one continuous motion, separating the fine coal from the coarse, and deflecting such coarse projected coal.

4. The method of delivering fuel which comprises elevating and tangentially projecting the fuel directly into the furnace, continuously passing a fluid through the fuel to separate the fine fuel, and intermittently deflecting the coarse fuel to distribute it to different parts of the furnace.

5. The method of feeding coal to a locomotive fire box which consists in elevating and projecting the coal directly into the furnace with one continuous motion, separating the

fine coal from the coarse coal and variably intercepting the path of the coarse coal to distribute it over the fire box.

6. In a locomotive having a fire box stoker means for projecting coal into said fire box, and means acting as a unit for settling the finer fuel and deflecting the coarse fuel.

7. In a locomotive, a fire box in combination with a mechanical stoker comprising a paddle structure positioned below and adjacent the firing door, means for rotating the paddle structure, means for feeding coal to said paddle structure whereby the coal will be elevated and thrown directly into the furnace with one continuous motion, means for deflecting the path of the projected fuel, means for passing a cooling fluid through said deflecting means, and means for projecting a part of said cooling fluid through the path of the projected coal.

8. In a locomotive, a fire box in combination

with a mechanical stoker comprising a revolvable paddle positioned below the firing door of said box, means for feeding coal to said paddle to be projected into the furnace, and fluid cooled means for changing the path of said coal, said fluid being utilized for separating the fine coal from said projected coal.

9. In a mechanical stoker, a rotatable paddle wheel mounted upon a horizontal axis, a casing therefor having a fuel inlet below said axis and between said axis and the path of the paddles of said paddle wheel, and a fuel outlet above said axis, and means for actuating said paddle wheel, said paddle wheel being adapted to lift the fuel from points about and below said inlet to said outlet and to project said elevated fuel through said outlet.

In testimony whereof I hereby affix my signature.

HENRY H. HAMILTON.
